UNITED STATES PATENT OFFICE.

HENRY C. SCHNEIDER, OF NEW YORK, N. Y.

DESIGN FOR A COMBINATION CIGAR-CUTTER, KNIFE, AND PENCIL.

48,793.

Specification for Design.

Patented Mar. 28, 1916.

Application filed January 28, 1916. Serial No. 74,863. Term of patent 14 years.

To all whom it may concern:

Be it known that I, HENRY C. SCHNEIDER, a citizen of the United States, residing at New York, in the county of New York and State of New York, have invented a new, original, and ornamental Design for a Combination Cigar-Cutter, Knife, and Pencil, of which the following is a specification, reference being had to the accompanying drawing, forming a part hereof, in which—

I claim:

The ornamental design for a combination cigar cutter, knife and pencil, as shown.

HENRY C. SCHNEIDER.
